UNITED STATES PATENT OFFICE

ALBERT ADOLPH SIGMUND BARKER, OF SOUTHCHURCH, ENGLAND, ASSIGNOR TO
DUNDAS SIMPSON, OF LONDON, ENGLAND

ELECTROTHERAPEUTIC HAIRBRUSH

Application filed January 21, 1931, Serial No. 510,305, and in Great Britain October 28, 1929.

The present invention relates to an improved hair brush of the type in which the circuit of a dry cell is complete whenever the brush is used.

5 According to the present invention a light and simple brush is provided with a back which supports a plurality of bristles mounted on and projecting through a flexible non-conducting support and divided in two 10 groups each of which is connected by a metal plate directly to one pole of a detachable and interchangeable dry cell carried within the backing. It will be noticed that the bristles of the brush are in direct simple circuit with 15 the dry cell and therefore carry a low tension current only. The invention does not include any construction in which currents induced by the aid of an interrupter are employed.

20 The invention is more particularly described with reference to the accompanying drawings in which:—

Figure 1 is a sectional elevation of one form of construction.

25 Figure 2 is a top plan view.

Figure 3 is a top plan view of the bristle support removed from the brush holder.

A moderately thick strip or piece of sheet rubber or the like flexible and non-conducting 30 material 1 has a number of metallic bristles 2 threaded into it, these bristles preferably having flat pin heads 3 adapted to make contact in two separate groups with plates 4, 5, each having springs 6, 7, respectively adapted 35 to form contact plates with contact strips 8, 9, respectively on a dry cell 10 held within a pocket 11 in the hollow back of the brush 12 of non-conducting material, this dry cell being held in position by a sliding cover 13.

40 The sheet of rubber 1 is held at its rim by the flange on the brush body 12.

The two sets of bristles 3 are insulated from one another by a cover strip or piece 14. It will be seen that the springs 6, 7, serve to 45 press the bristles outwards, so that the brush is elastic in use. Further, that there is no flow of current through the dry cell until contact is made through the points of the bristles in the two separate groups by contact 50 with the human head or hair.

I declare that what I claim is:—

An electro-therapeutic hair brush comprising in combination a non-conductive body portion having a hollow back, said back having a depending flange provided with an inwardly projecting portion forming a recess at its peripheral edge, an arched sheet of rubber held within said recess and supporting a series of metallic bristles mounted therein with retaining heads protruding inwardly therethrough, a pair of arched contact plates adapted to contact with the heads of the bristles and divide them into two groups, a detachable battery mounted within the hollow of the back, and a pair of resilient conductive connecting devices between the separate plates and the battery, said devices also serving for resiliently opposing the elastic inward movement of the bristles and their supports.

In witness whereof, I have hereunto signed my name this 3 day of January, 1931.

ALBERT ADOLPH SIGMUND BARKER.
